US00D526109S

(12) **United States Design Patent** (10) **Patent No.:** **US D526,109 S**
(45) **Date of Patent:** **** Aug. 1, 2006**

(54) **MATERIALS HANDLING CONTROLLER**

(75) Inventors: **Brent A. Bergman**, Yorkshire, OH (US); **Robert J. Henshaw**, Newnan, GA (US); **Russell J. Kroll**, Atlanta, GA (US); **Philip D. Palermo**, Marietta, GA (US); **Steven R. Pulskamp**, New Bremen, OH (US); **Craig J. Rekow**, Troy, OH (US); **Douglas J. Rinderle**, St. Henry, OH (US); **Adam M. Ruppert**, Wapakoneta, OH (US)

(73) Assignee: **Crown Equipment Corporation**, New Bremen, OH (US)

(**) Term: **14 Years**

(21) Appl. No.: **29/213,796**

(22) Filed: **Sep. 23, 2004**

(51) **LOC (8) Cl.** **12-05**

(52) **U.S. Cl.** **D34/35; D14/415**

(58) **Field of Classification Search** **D34/28, D34/34, 35; D14/415, 412, 416; 244/234, 244/236; 280/43.12; 187/222, 224; D12/179**

See application file for complete search history.

(57) **CLAIM**

The ornamental design for a materials handling controller, as shown.

DESCRIPTION

FIG. 1 is a perspective view of a materials handling controller showing our new design, the view taken from left front of the controller;

FIG. 2 is an elevational view of the left side of the controller; FIG. 3 is an elevational view of the right side of the controller;

FIG. 4 is a top view of the controller;

FIG. 5 is an elevational front view of the controller; and, FIG. 6 is an elevational back view of the controller.

The bottom of the controller is plain and unornamented. The broken line showing in the figures is for illustrative purposes only and forms no part of the claimed design.
